LOCK CONSTRUCTION

Henry F. Keil, Scarsdale, N. Y., assignor to
 Francis Keil & Son, Inc., a corporation of New
 York

Application February 19, 1934, Serial No. 711,976

15 Claims.

(Cl. 70—46)

This invention relates to key-controlled lock mechanism.

One of the objects of this invention is to provide a simple, thoroughly practical, and reliable key-controlled lock mechanism in which assembly and disassembly of the parts may be readily and inexpensively achieved. Another object is to provide a construction which will be thoroughly dependable in action and rugged in construction. Another object is to provide a lock construction in which repair or replacement of parts may be dependably accommodated and thus avoid the great inconvenience, annoyance, and expense in the course of repairs of attempting to duplicate or replace broken or worn out parts. Another object is to provide a construction which may be inexpensively and rapidly manufactured. Other objects will be in part obvious or in part pointed out hereinafter.

20. The invention accordingly consists in the features of construction, combinations of elements, and arrangements of parts as will be exemplified in the structure to be hereinafter described and the scope of the application of which will be indicated in the following claims.

In the accompanying drawing in which is shown one of various possible embodiments of my invention,

Figure 1 is a vertical sectional view;

30. Figure 2 is a plan view as seen from the top in Figure 1 but showing the parts in relation to a door, or the like;

Figure 3 is a plan view of a part shown in Figure 1 but omitted in Figure 2;

35. Figure 4 is a transverse sectional view as seen, for example, on the line 4—4 of Figure 1;

Figure 5 is an end view, as seen from the left in Figure 1, of the key plug or cylinder, and

40. Figure 6 is a perspective view of a connecting bar.

Similar reference characters refer to similar parts throughout the several views of the drawing.

Referring first to Figure 1, I have shown a casing generally indicated at 10 and constructed, as hereinafter described, so as to facilitate die casting, though it is to be understood that the casing 10 may be constructed in any suitable manner other than die casting, if desired. Casing 10 is in general of cylindrical shape and has a cylindrical bore 11 (Figures 1 and 4) in which is rotatably received the key plug 12 or which likewise is cylindrical in shape. Key plug 12 is provided with any suitable tumbler devices or tumbler-controlling devices and illustratively these may

take the form of the so-called wafer type of tumbler, such as is shown at 13 in Figure 4, there being a suitable number of these tumblers, illustratively five, as indicated in Figure 1, being received in suitable recesses 14 extending transversely through the key cylinder 12.

These wafer tumblers 13, usually in the form of sheet metal stampings, are pressed downwardly, as viewed in Figure 4, each by a spring 15 carried in a suitable recess or extension of the recess 14 in the key plug 12.

When thus pressed downwardly the lower ends 13a (Figure 4) enter a longitudinally extending slot or recess 16 in the bottom of the bore 11 in the casing 10, and thus preclude rotation of the plug 12 relative to the casing 10. The plug 12 is provided with a key-receiving groove 17 extending centrally and lengthwise thereof and all of the tumblers 13 have a hole therethrough through which the key may pass. Accordingly, when the proper key is inserted, each tumbler is raised by the key against the action of the spring 15 by an amount sufficient to bring the tumbler within the peripheral confines of the plug 12, whereupon rotation of the plug 12 by the key may take place. Diametrically opposite the tumbler-receiving slot 16 is a similar tumbler-receiving slot 18 with which the tumblers may similarly coat after a 180° rotation of the key plug 12. In so far as this tumbler construction and action are concerned, they may take any suitable form and the above is intended to be illustrative.

The right-hand end of the key plug 12 is flanged as at 12a to be received within a rabbet 19a of the front cylindrical flange 19 at the right-hand end and integrally formed as a part of the casing 10, flange 19 resting against the door or like member indicated at 20 in Figure 2. Flange 12a thus limits movement of the key plug 12 in a direction toward the left relative to the casing 10.

The left-hand end of the bore 11 in casing 10 is closed by the left-hand or rear end wall 10a of the casing 10, that wall, however, being provided with a hole 10b of a diameter slightly in excess of the width of the connecting or operating bar 21 (Figures 2 or 6) which is to connect the key plug 12 to any suitable bolt-operating mechanism diagrammatically indicated in Figures 1 and 2 at 22. The connecting bar 21, at its one end, has lateral projections 21a—21b, giving the right-hand end, as viewed in Figure 6, substantially the shape of a T. Accordingly, before inserting the key plug 12 into the bore 11, the connecting bar 21 is inserted through the hole 10b in the end wall of casing 10, this insertion being done by way of the

bore 11 itself; the end projections 21^a—21^b prevent the connecting bar 21 from passing through this hole 10^b.

Now the left-hand end of the key plug 12 is provided with a transverse slot 12^b (Figures 1 and 5), the key plug 12 being of a length sufficient to come virtually up against the inner face of the end wall 10^a, the right-hand end of the connecting bar 21 being received within the slot 12^b of the key plug 12. Thus, a secure driving connection between key plug 12 and connecting bar 21 is insured.

Adjacent the left-hand end of the key cylinder 12, the latter is provided with a peripheral groove or recess 12^c (Figure 1) with which coacts a means, about to be described, for preventing the key plug 12 from moving toward the right and hence from becoming disassembled from the casing 10.

20 The casing 10 is in general of cylindrical shape (Figure 4) but at its upper part and extending lengthwise thereof and integrally formed therewith is a chamber forming portion generally indicated at 30, being provided with side walls 30^a—30^b (Figure 4), an abutment 30^c forming the left-hand end wall (Figure 1) and a right-hand end wall 30^d formed virtually by the front flange 19 of the casing 10.

30 The abutment 30^c (Figures 1 and 2) is provided with a channel or hole 31 communicating with the bore 11 of the casing 10 and it is in alignment with the peripheral groove 12^c (see Figure 1) in the left-hand end of the key plug 12. Through this channel 31 there is inserted any suitable means, 35 such as and preferably a pin 32 headed as at 32^a, the pin being of sufficient length to extend into the peripheral slot or groove 12^b in the plug 12, thus preventing axial movement of the plug 12 relative to the casing 10.

40 To hold the pin 32 in place and to preclude ready access thereto, I undercut or groove the opposed side walls 30^a—30^b (Figure 4) of the chamber-forming portion 30, as at 30^e and 30^f, thus forming ways, or the like, to receive a closure member 33 (Figure 3) dovetailed as at 33^a and 33^b to mate with the undercut grooves 30^e and 30^f, respectively, the parts being so dimensioned that when the closure member 33 is slid into place (in a direction from the left to the right as viewed in Figures 1 and 2) there is a snug fit sufficient to hold the member 33 against involuntary movement; moreover, I may also shape the parts as at 33^a and 33^b (Figure 3) and as at 30^g and 30^h (Figure 2) to form substantially a wedge, whereby the closure member 33 may be forced home and wedged into closing position. Member 33 (Figure 3) has a transverse groove 33^c whereby the using of the fingernail, or a screw driver, or the like, may be made to slide the member 33 out of the ways 30^e—30^f and thus expose the chamber 30^k (Figures 1 and 4) formed in the member 30, and thus also to make accessible the assembly member 32.

55 In this chamber 30^k, I place extra parts, such as extra tumblers 13^a, extra springs 15^a, extra assembly members or pins 32^b, and like small parts of the mechanism. In this condition the lock construction is sold and installed.

60 Should occasion arise to repair the construction, disassembly is readily achieved by removing the closure 33 and withdrawing the assembly member 31, whereupon the key plug 12 may be withdrawn from casing 10. Any extra parts that 75 may be needed for repair are found in the cham-

ber 30^k that is thus uncovered by removal of closure 33.

As above mentioned, the front flange 19 (Figure 2) abuts against the front face of the door 20, casing 10 being received inside a suitable hole 20^a in the door. The inside face of the door has secured to it a sheet metal plate 34 through which are to be passed screws 35—36 threaded into side lugs 37—38 integrally formed with the casing 10, thus to securely clamp the construction 10 in the hole 20^a in the door 20. But in installation great difficulty, loss of time, and inconvenience, are sustained in attempting to catch the screws 35—36 in the lugs 37—38, respectively, and accordingly, I provide the left-hand ends of the latter with large funnel-shaped entry ends 37^a—38^a, respectively, being preferably in diameter several times the diameter of the screws. Thus the screws are easily assembled to the threaded lugs 37—38.

The bolt-operating mechanism 22 is, of course, mounted on the left-hand face of the door 20 (Figure 2) and goes over the plate 34 above described.

Moreover, the casing 10 with its integrally formed features above described, is of such configuration that it lends itself readily to die casting and thus to less expensive construction.

It will thus be seen that there has been provided in this invention a construction in which the various objects hereinbefore mentioned, together with many thoroughly practical advantages, are successfully achieved.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

I claim:—

1. In a lock construction, in combination, a casing having a bore for rotatably receiving a key plug, the rear end of the bore being closed by a wall having a hole therein, a connecting bar passing through the hole and having means on the inner end thereof to prevent it from going through the hole, a key plug received in the bore and having at its end a recess for non-rotatable reception of the inner end of said connecting bar, said key plug having a peripheral groove, and said casing having an aperture opening into the bore in alignment with said groove, means extending from said aperture into said peripheral groove for holding said plug against axial movement, said aperture terminating at an outer portion of said casing, and means for closing over said aperture at said outer end.

2. In a lock construction, in combination, a casing having a bore for rotatably receiving a key plug, the rear end of the bore being closed by a wall having a hole therein, a connecting bar passing through the hole and having means on the inner end thereof to prevent it from going through the hole, a key plug received in the bore and having at its end a recess for non-rotatable reception of the inner end of said connecting bar, said key plug having a peripheral groove, and said casing having an aperture opening into the bore in alignment with said groove, means extending from said aperture into said peripheral groove for holding said plug against axial movement, said aperture terminating at an outer portion of said casing, said casing having a chamber for receiving spare parts adjacent the outer terminus of said aperture, and means operative to close

both said chamber and the outer terminus of said aperture.

3. In a lock construction, in combination, a casing having a bore for rotatably receiving a key plug, the rear end of the bore being closed by a wall having a hole therein, a connecting bar passing through the hole and having means on the inner end thereof to prevent it from going through the hole, a key plug received in the bore and having at its end a recess for non-rotatable reception of the inner end of said connecting bar, said key plug having a peripheral groove, and said casing having an aperture opening into the bore in alignment with said groove, means extending from said aperture into said peripheral groove for holding said plug against axial movement, said aperture terminating at an outer portion of said casing, said casing having a chamber for receiving spare parts adjacent the outer terminus of said aperture, the side walls of said chamber being shaped to form slideways, and a closure member slidably received in said slideways for closing said chamber and extending also over the outer terminus of said aperture.

4. In a lock construction, in combination, a casing having a key plug rotatably mounted therein, said casing and key plug having coacting tumblers and springs and said casing having recess means separated from the exterior of said casing by a wall and said tumblers being adapted to coact with said recess means, means for detachably holding said plug against axial movement relative to said casing, means extending about said wall to form therewith a chamber for spare parts of the lock mechanism and means closing said chamber and preventing access to said detachable holding means.

5. In a lock construction, in combination, a casing having a key plug rotatably mounted therein, said casing and key plug having coacting tumblers and springs, said casing having a portion thereof hollowed out to form a chamber for receiving spare parts of the lock mechanism, and opening on an exterior surface thereof, and means to close said chamber to retain such parts therein but also so as to provide ready access thereto when needed.

6. In a lock construction, in combination, a casing shaped to enter a recess in the member to which the lock construction is adapted and having a key plug rotatably mounted therein, said casing and key plug having coacting tumblers and springs, said casing having a front escutcheon to rest against the front face of said member, and means to the rear of said escutcheon and opening on an external surface of said casing forming a chamber with removable closure therefor for completely enclosing and for holding spare parts of the lock mechanism, whereby said chamber is inaccessible from the exterior of said member.

7. In a lock construction, in combination, a casing to be set into a recess in a member to which the lock construction is attached and having flange means for coacting with the front face of said member, a key plug rotatably mounted within said casing, said key plug and casing having coacting tumbler means, means forming a plurality of chambers within said casing and integral therewith and opening on an external surface thereof to the rear of said flange means, and a slidable cover adapted to completely close all of said plurality of openings, whereby, when said lock construction is attached to said member, said

chamber-forming means and said cover are inaccessible from the exterior of said member.

8. In a lock construction, in combination, a casing to be set into a recess in a member to which the lock construction is attached and having flange means for coacting with the front face of said member, a key plug rotatably mounted within said casing, a locking pin for said plug, said casing having a front escutcheon for resting against the front face of said member, said casing having a plurality of chambers located to the rear of said escutcheon, one of said chambers being substantially rectangular in form and having a relatively large capacity for containing spare parts of the lock mechanism and another of said chambers being of relatively small capacity for holding said locking pin to retain said key plug within said casing, whereby, when said lock construction is attached to said member, said chamber-forming means and said cover are inaccessible from the exterior of said member.

9. In a lock construction, in combination, a casing having a key plug rotatably mounted therein, said casing and key plug having coacting tumblers and springs, said casing having a portion thereof hollowed out to form a chamber for receiving spare parts of the lock mechanism, said chamber having beveled edges along a portion of its length, and means to close said chamber, said means comprising a spatulate cover plate, the edges of the broader portion of which are beveled in such a manner as to coact and lock with said beveled edges of said chamber.

10. In a lock construction, in combination, a casing to be set into a recess in a member to which the lock construction is attached and having flange means for coacting with the front face of said member and said casing having a key plug rotatably mounted therein, said casing and key plug having coacting tumbler means, said casing having said flange means formed into a front escutcheon for resting against the front face of said member, means to the rear of said escutcheon for adjustably coacting with said member and said casing to hold the latter in said recess throughout a certain range of different depths of said recess, and means always effective throughout said range of different depths of recess and positioned to the rear of said escutcheon and opening on an external surface of said casing forming a chamber for holding spare parts of the lock mechanism, a cover plate for said chamber, and means also positioned to the rear of said escutcheon for holding said cover plate in covering position, whereby, when said lock construction is set into said recess and attached to said member, said cover plate is exposed to the recess in said member but not to the exterior of said member.

11. In a lock construction, in combination, a casing to be set into a recess in a member to which the lock construction is attached and having flange means for coacting with the front face of said member having a key plug rotatably mounted therein, said casing and key plug having coacting tumblers and springs, said casing having a front escutcheon for resting against the front face of said member and an opening to the rear of said escutcheon, said opening having beveled edges adjacent a portion of the top edge thereof, and a spatulate cover for said chamber, the broadened portion of said spatulate cover comprising angular flanges adapted to engage said beveled edges of said chamber.

12. A casing having mounted therein and co-
acting therewith key controlled means, said cas-
ing having a front flange through which said
means is made accessible for the insertion of a
key, said flange abutting against the outer face
5 of the member on which the casing is mounted,
said casing projecting rearwardly of said flange
into a recess in said member, and means forming
a chamber with a movable closure for the open
10 end thereof for holding the spare parts of said
key controlled means, the open end of said cham-
ber and said movable closure being exposed to
said recess.

13. A casing having mounted therein and co-
15 acting therewith key controlled means, said cas-
ing having a front flange through which said
means is made accessible for the insertion of a
key, said flange abutting against the outer face
of the member on which the casing is mounted,
20 said casing projecting rearwardly of said flange
into a recess in said member, means forming a
chamber for holding spare parts of said key con-

trolled means, and a cover for said chamber for
closing the latter to retain therein said spare
parts, said cover being exposed to said recess.

14. A casing having mounted therein and co-
acting therewith key controlled means, said cas-
ing having a front flange through which said
means is made accessible for the insertion of a
key, said flange abutting against the outer face
5 of the member on which the casing is mounted,
said casing projecting rearwardly of said flange
into a recess in said member, means forming a
chamber in said casing and an otherwise unse-
cured cover for said chamber exposed to said re-
cess.

15. A lock construction as claimed in claim 15
10 in which there is also means for holding said
key plug in assembled relation to said casing,
said last-mentioned means being positioned to be
substantially inaccessible except upon changing
the position of said cover plate relative to said 20
chamber.

HENRY F. KEIL.
